J. T. AUSTIN

COMBINATION ORGAN STOP ACTION

Filed Sept. 4, 1920

J. T. Austin
INVENTOR.

BY

Frank J. Sutherland
ATTORNEY.

UNITED STATES PATENT OFFICE.

JOHN T. AUSTIN, OF HARTFORD, CONNECTICUT, ASSIGNOR TO THE AUSTIN ORGAN COMPANY, OF HARTFORD, CONNECTICUT, A CORPORATION OF CONNECTICUT.

COMBINATION ORGAN-STOP ACTION.

Application filed September 4, 1920. Serial No. 408,216.

To all whom it may concern:

Be it known that JOHN T. AUSTIN, a citizen of the United States, residing at Hartford, in the county of Hartford and State 5 of Connecticut, has invented certain new and useful Improvements in Combination Organ-Stop Actions, of which the following is a specification.

This invention relates to combination 10 organ stop actions. A type of such actions is shown in Letters Patent No. 1,279,492 issued to me Sept. 24, 1918 and to which reference may be had. I have a number of motives in view among them being the 15 provision of simple means by which a trace, constituting part of such an action, can be positively and accurately operated.

In the drawings accompanying and forming part of the present specification I have 20 shown in detail one of the several forms of embodiment of the invention which to enable those skilled in the art to practice the same will be set forth fully in the following description. Clearly I am not restricted to 25 this disclosure. I may depart therefrom in several respects within the scope of the invention defined by the claims following said description.

Referring to said drawings:

30 Figure 1 is a diagrammatic side elevation of combination organ stop mechanism involving the invention.

Fig. 2 is a longitudinal section of a catch member.

35 Fig. 3 is a perspective view of part of an organ action equipped with stop mechanism involving the invention.

Fig. 4 is a detail in elevation on a slightly 40 enlarged scale of the forward portion of a trace and a cooperative magnet.

Like characters refer to like parts throughout the several views.

The organ stop mechanism to which I have referred in the patent hereinbefore 45 identified, involves a series of traces. One of these traces is shown and is denoted by 2. On its side are mounted a number of actuators as I call them. These actuators, for purpose of clearness are not shown in the 50 drawings. The trace 2 like its companions has an advance movement toward the right in Fig. 1 and a retractive movement obviously toward the left in this view. The means by which the advancing movement is 55 effected, in the present case constitutes one

of the important features of the invention and is electrically brought about.

A trace which of course may be like any one of those shown and described in the Letters Patent to me, hereinbefore identified, is 60 supported by the bed 3 which is channeled to receive the trace and others like it, for sliding movement. The trace 2 is advanced in the manner hereinbefore described and is retracted by a spring as 4 acting against 65 it and also against the bed or base 3 and is customarily of wood.

As I have already observed the advancing effect of the trace 2 is electrically accomplished and is desirably brought about by 70 a magnet 5 of solenoid type, one terminal of the solenoid being connected by the wire 6 with the battery 7 constituting a suitable source of electrical energy. The wire 6 is connected to one pole of the battery, the wire 75 8 leading from the other pole thereof, to the switch 9 operated mechanically for instance by the button switch 10, the lever or equivalent part of the switch co-operating with a contact on the wire 11 which leads to the 80 magnet 12, the wire 13 constituting a continuation of the wire leading from the magnet 12 to the terminal of the solenoid 5 opposite to that to which the wire 6 is connected. As shown the rock lever 16 is pivoted to a 85 bearing 3' rising from the bed 3. Upon the closing of the switch 9 through the action of the push button or equivalent part 10, the circuit involving the solenoid 5 and the electro-magnet is closed so as to energize 90 both magnets.

The core of the electro-magnet 5 is designated by 14 and as shown is jointed to the link 15 which is pivotally connected at its outer end to the rock lever 16 mounted on 95 the supporting structure or bed 3 and pivoted to the block 17 at the rear end of the rod or impeller 18. The impeller is advanced in the present case through the action of the solenoid 5 and is retracted by 100 the spring 19 acting respectively against the link 15 and block 17. The impeller 18 and other parts in fact are shown as occupying their back positions in Fig. 1.

The trace 2 is shown as having at its forward end a notch 20 the back and front walls of which have projections 21 and 22 respectively to enter cylindrical seats 23 and 24 in the ends of the cylindrical member 25 set into the notch or aperture 20. The back 110

aperture 23 is of very much larger size or diameter than the front aperture 24 in view of which circumstance, the rear portion of the member 25 may be tipped up. This member 25 constitutes an armature for the electro-magnet 12.

The impeller 18 is shown as having fastened to its forward lower side the operating piece 26 of angular form in view of which 10 circumstance the rod 18 becomes an actuator for the trace 2. If the impeller 18 be advanced when the other parts are occupying the position shown in Fig. 1, nothing can be accomplished. If, however, the rear end 15 of the cylindrical member 25 be tipped up into the path of the operating piece 26 it will be clear that the operating part 26 on the advance of the impeller 18 will engage the rear end of the cylindrical member 25 20 and thus move the trace 2 forwardly.

Although for the sake of simplicity only one trace is shown herein, it will be understood that in practice there are a group of these traces 2 and that there is a 25 magnet as 12 co-operative with each trace, the solenoid 5 however being common to a group or series of traces. It will be assumed that a trace is to be advanced. In this event the button 10 will be manipulated to operate the switch lever 9 to close the circuit including the electro-magnet 12 and the solenoid 5. This draws the rear end of the member 25 upwardly so that on the forward movement of the selected impeller 30 18 the operating piece 26 will strike the rear end of the catch or cylindrical member 25 and thus advance the trace 2. On the de-energization of the solenoid 5 and magnet 12 by opening their circuit, the part 25 will 35 40 of course drop and the spring 4 will return the trace 2 to its normal position and practically concurrently the spring 19 will return the impeller 18 and parts associated therewith to their original positions.

I might say that upon the closing of a circuit, the armature 25 electrically acts very much quicker than the solenoid 5.

I have termed the part 18 broadly an "actuator." Of course, the trace 2 in practice carries also what are known as "actuators" and which are sometimes known as "cams". The part 18 can, therefore, be properly considered as an actuator because it does actuate or operate something else.

55. What I claim is:

1. An organ stop action comprising a trace, a magnet and its armature, the armature being mounted on the trace, the magnet when energized acting to attract its armature, an impeller acting on its advance, to operate the armature when it is thus attracted by its magnet, and means for advancing the impeller.

60. 2. A combination organ stop action comprising a trace, an impeller, a magnet and

its armature, the armature being mounted on the trace and the magnet when energized attracting its armature, an impeller on its advance engaging the armature when it is thus attracted, and advancing the trace, 70 and electrical means for effecting the advance of the impeller.

3. A combination organ stop action comprising a trace, an impeller, a magnet and its armature, the armature being mounted 75 on the trace and the magnet when energized attracting its armature, the impeller on its advance engaging the armature when it is thus attracted, to advance the trace, an electrically operated device associated with the impeller and an electric circuit including the magnet and the electrically operated device, the circuit when closed causing the energization of the electrically operated device and the magnet, and the electrically 80 operated device when energized acting to advance the impeller to effect the advance of the trace.

4. A combination organ stop action comprising a trace, a magnet and its armature, 90 the armature being mounted on the trace and the magnet when energized attracting its armature, an impeller adapted on its advance to engage the armature when it is thus attracted to advance the trace, a solenoid the core of which is connected with the impeller to cause the advance of the impeller and hence the advance of the trace 95 on the energization of the solenoid, and an electric circuit including the magnet and the solenoid. 100

5. A combination organ stop action comprising a trace, a magnet and its armature, the trace having a notch in which the armature is mounted and the magnet when energized acting to attract its armature, an impeller, and means for reciprocating the impeller whereby on its forward movement it engages the armature when it is thus attracted, to advance the trace. 105

6. A combination organ stop action comprising a trace, a magnet and its armature, the trace having a notch in which the armature is mounted, the armature having seats in its ends, the rear seat being larger than the front seat, and the walls of the notch having projections which enter the seats, the magnet when energized acting to attract its armature and thus tip it on the front projection, an impeller, and means for reciprocating the impeller, whereby on its forward movement it engages the armature when the same is attracted, to advance the trace. 115

120. In testimony whereof I affix my signature. 125
